(No Model.)

S. W. BARR.
STORE SERVICE APPARATUS.

No. 432,852.

Patented July 22, 1890.

Attest,
Geo. T. Smallwood,
Walter Allen

Inventor:
Samuel W. Barr.

By Knight Bros. Atty's

UNITED STATES PATENT OFFICE.

SAMUEL W. BARR, OF MANSFIELD, OHIO.

STORE-SERVICE APPARATUS.

SPECIFICATION forming part of Letters Patent No. 432,852, dated July 22, 1890.

Application filed November 18, 1889. Serial No. 330,678. (No model.)

To all whom it may concern:

Be it known that I, SAMUEL W. BARR, a citizen of the United States, and a resident of Mansfield, in the county of Richland and State 5 of Ohio, have invented certain new and useful improvements in Store-Service Apparatus; and I do hereby declare the following to be a full, clear, and exact description of the invention, such as will enable others skilled in the 10 art to which it appertains to make and use the same.

My invention relates to improvements on the cash-carrier apparatus described, shown, and claimed in Letters Patent No. 357,449, 15 dated February 8, 1887, and issued to me.

My improvements consist in the novel features of construction hereinafter described, and pointed out in the claims.

In order that my invention may be fully understood, I will proceed to describe it with reference to the accompanying drawings, in which—

Figure I is a side elevation of a single station, the lever being shown in normal position and a carrier approaching the station. Fig. II is a top view of the same. Fig. III is a bottom view of the lever.

Referring to Figs. I, II, and III, 1 is a station-support secured to a ceiling or overhead floor, which may be in the form of a gas-pipe or tube of any suitable metal. To the lower end of this support I apply a block or head 2, in the form of an elbow and constructed with a bell or mouth-piece 3 for its attachment to 30 the support, with downwardly-curved cheek-plates or flanges 4, having upwardly-extending ears 5, and providing a lever-bearing and a slot or opening 6 for the lever to work in, and with an upwardly-extending boss or projection 7, with which the stay-wire is connected.

The block or head is braced to the ceiling or overhead floor by the following means:

8 is a screw-rod rigidly secured to the boss 45 or projection and extending in an inclined position therefrom. Loosely mounted on this screw-rod is a yoke 9, having horns 10—one at each end—and working on the screw-rod, outside the yoke, is a nut 11. Secured to the 50 ceiling or overhead floor by means of eye-screws 12 is the stay-wire 13, passed beneath the yoke and screw-rod and over the horns of

the yoke to the eye-screws. By means of the screw-rod and nut the yoke is adjusted on the screw-rod for tightening or loosening the 55 track-wires.

14 is the operating or propelling lever cored out to one-eighth of an inch at the sides and top, and the lower edge left open, except a boss 15 in the center, through which a pivot 60 screw or bolt 16 is passed for journaling the lever to the lower ends of the cheek-plates or flanges within the slot or opening. Journaled within the lever—one on each side of the boss—are sheaves or pulleys 17. The lever is constructed with a short bent arm 18 at its rear end, having a handle 19. Over the front end of the lever and integral therewith is a block 20, perforated to receive the arms 22 of a spring-catch loop 21, adjustable in the 70 block and secured in desired position by set-screws 23. The spring-catch is provided with a rubber tube or sleeve 24 at its center. The ears 5 on the cheek-plates or flanges are formed with a series of holes or perforations 75 25, 26, and 27 for an adjustable check cross-pin 28, which limits or controls the upward movement of the inner end of the lever by forming a stop thereto. The cross-pin can be moved to either pair of holes or perforations 80 and will regulate the spread of the track-wires or force applied to the carrier to suit the distance the carrier has to travel or the length of the track-wires or line. The lever striking the cross-pin when it is in the front or first 85 holes or perforations 25 will spread the track-wires about six inches. If the cross-pin is moved to the intermediate or second holes or perforations, the lever will spread the track-wires about seven inches. If the cross-pin is 90 moved to the rear or third holes or perforations, the spread of the track-wires will be about eight inches, and when the cross-pin is removed and the lever turned to a vertical position, the spread of the track-wires will be 95 about ten inches, equal to the distance between the outward circumference of the pulleys or sheaves 17 in the lever. Thus the spread of the track-wires or force to the length of line or the distance the carrier has to travel 100 is gaged.

29 is the upper track-wire, and 30 is the lower track-wire, having their ends secured to a connection in the form of a small chain

or strap 31, which moves through the interior of the lever around the pulleys or sheaves. A spring in the form of a rubber sleeve or bead is slipped on the lower track-wire before it is fastened to the chain or strap to provide a bumper 32 to cushion or check the carrier when the latter passes under the spring-catch.

33 is a carrier propelled by two track-wires passing between the wheels and spread at the rear of the carrier. The carrier may have two or four wheels, and is cut away at one side to permit it to pass a support for the track-wires between stations.

15 The operative positions of the lever and track-wires are shown in dotted lines in Fig. I. Instead of a chain or strap, I may employ a cord for connecting the ends of the track-wires, or I may continue the latter through 20 the pulley independent of the block or head.

Having thus described my invention, the following is what I claim as new therein and desire to secure by Letters Patent:

1. The combination, with a head or block, 25 of an operating-lever pivoted thereto, the upper and lower track-wires located one wire over the other wire, and the connection passed lengthwise of and returned through the lever by which the track-wires are connected, substantially as described.

2. The combination, with a head or block, 30 of an operating-lever pivoted thereto, the upper and lower track-wires, and the connection by which the track-wires are connected and within which the lever operates to spread 35 or close the track-wires, substantially as described.

3. The combination, with a head or block, of an operating-lever pivoted thereto, the upper and lower track-wires connected together 40 through the lever, and the chain by which the track-wires are connected, substantially as described.

4. The combination, with a head or block, 45 of an operating-lever pivoted thereto, the upper and lower track-wires, the connection for the track-wires within which the lever operates, and the bumper secured to the lower wire at its juncture with the connection, substantially as described.

5. The combination, with a head or block, 50 of the operating-lever pivoted to the head or block having sheaves or pulleys, one on each side of the pivot, the upper and lower track-wires, and the connection for the track-wires 55 on which the sheaves or pulleys run, substantially as described.

6. The combination of the head or block, the operating-lever, an adjustable stop for limiting the throw of the lever, and the upper and 60 lower track-wires connected together through the lever, substantially as described.

7. The combination of the head or block having cheek-plates formed with a series of 65 holes, a check cross-pin adjustable in said holes, an operating-lever pivoted to the cheek-plates, and the upper and lower track-wires connected together through the lever, substantially as described.

SAMUEL W. BARR.
